United States Patent Office

Des. 183,712
Patented Oct. 21, 1958

183,712

BEACH BAG OR SIMILAR ARTICLE

Marilyn Blaivas, Lawrence, N. Y.

Application February 5, 1958, Serial No. 49,515

Term of patent 3½ years

(Cl. D87—3)

Figure 1 is a front elevational view of a beach bag or similar article showing my new design;

I claim:

The ornamental design for a beach bag or similar article, substantially as shown.
